Inventor:
George C. Waterhouse,

UNITED STATES PATENT OFFICE.

GEORGE C. WATERHOUSE, OF NEW ALBANY, INDIANA, ASSIGNOR TO JOHN S. FITE AND JOSIAH F. PERRIN, BOTH OF SAME PLACE.

SHUTTER-FASTENER.

SPECIFICATION forming part of Letters Patent No. 340,262, dated April 20, 1886.

Application filed January 8, 1886. Serial No. 188,010. (No model.)

To all whom it may concern:

Be it known that I, GEORGE C. WATERHOUSE, a citizen of the United States, and residing at New Albany, in the county of Floyd 5 and State of Indiana, have invented a certain new and useful Improvement in Locking Devices for Shutters, of which the following is a specification.

My invention relates to that class of locking devices used for holding window-shutters in their closed positions; and my invention consists of a locking-lever adapted to a staple in the shutter, and constructed and attached to the sill, and adapted to be locked in place by 15 the sash, all as fully set forth hereinafter, and as illustrated in the accompanying drawings, in which--

Figure 1 is a transverse section of sufficient of a sill, shutter, and sash to illustrate the arrangement of my improved shutter-fastener, shown in connection with the said parts; Fig. 2, the same, showing the parts in a different position; Fig. 3, a section on the line 1 2, Fig. 1; Fig. 4, a plan view of the parts shown in 25 Fig. 1, except the sash; Fig. 5, a perspective view of the yoke-plate.

A represents the sill of the window, and B is one of the blinds, which is hinged, as usual, to the side of the frame, and C is the lower 30 sash. To the sill is secured the blind-lock, which consists of a lever, H, having two arms, b d, extending from opposite sides of the central portion where the trunnions a are arranged, the said arms being at an angle to 35 each other, as shown, so that when one of the arms lies upon the face of the sill, as shown in Figs. 1 and 2, the other arm will occupy an inclined position. The trunnions a cross the lever H at a point below the lower edge thereof, as shown best in Fig. 3, and may lie within a groove or recess, x, in the face of the sill, and also extend into grooves y y in the under 40 side of a yoke-plate, D, which extends over the lever and over the trunnions, and is secured to the sill, thereby retaining the lever in its position and protecting it from injury by blows tending to displace it. In the construction shown the yoke-plate D is secured to the sill by screws e passing through openings f of the yoke-plate.

To the inside of the shutter B is secured a metallic loop or staple, I, so arranged that when the lever H is tilted to the position shown in Fig. 2 a lug, i, thereof will enter the said staple, and will thereby prevent the 55 opening of the shutters, and inasmuch as the trunnions a take their bearings against the sides of the grooves x in the sill, the latter, instead of the yoke, serves to resist any strains resulting from the outward thrust of the shutter when the lever is in engagement with the staple I, so that the shutter does not depend upon the yoke-fastenings for securing it in position. When the sash C is raised, the lever H, owing to the superior weight of the 60 arm b, will occupy the position shown in Fig. 1, the arm b lying upon the face of the sill and the lug i being out of engagement with the staple, so that the shutter may be freely opened; but when the sash C is brought down to the 65 position shown in Fig. 2, it will depress the arm d, elevate the arm b, and lock the lever to the staple, thereby preventing the shutter from being opened from the outside or from the inside, until the sash C is raised, while the 70 act of lifting the sash will release the lever from its connection with the shutter.

In order to permit the sash C to be brought closely down against the sill, a recess, w, is formed in the lower edge of the sash to receive 75 the end of the arm d.

It will be seen that by providing the lever H with trunnions arranged so as to occupy a position within the notch x, and by constructing the yoke with recesses y to receive the 80 trunnions, the yoke assists in maintaining the lever in its position at right angles to the shutter when closed, and also to hold the trunnions in their socket-bearing x', the clamping of the trunnions between the yoke and the 85 sill securing a positive and firm bearing for the trunnions without the necessity of making special fittings required when the trunnions are above the usual supporting-plate.

Without limiting myself to the precise construction and arrangement of parts shown, I claim--

1. The combination, with a window-shutter provided with a fixed staple, I, and with a sash, C, of a lever, H, pivoted upon the sill 90

and having two arms, *b d*, at an angle to each other extending from opposite sides of the trunnions, one of the arms having a lug for engaging with the staple, and the other extending beneath the sash, substantially as set forth.

2. The combination, in a shutter-lock, of a lever having two arms at an angle to each other, trunnions extending across the lever to and projecting below its lower edge, and a

yoke-plate having ears *f*, and recessed to receive the trunnions, substantially as described.

In testimony whereof I have signed my name to this specification in the presence of two subscribing witnesses.

GEORGE C. WATERHOUSE.
